SINKER OR WEB HOLDER CONTROL

Robert H. Lawson, Pawtucket, and Arthur N. Cloutier, Lonsdale, R. I., assignors to Hemphill Company, Central Falls, R. I., a corporation of Massachusetts

Application April 9, 1929, Serial No. 353,835

9 Claims. (Cl. 66—108)

The present invention has to do with the control of the sinkers or web holders in a knitting machine of the independent needle type such as disclosed in the patent to Hemphill 933,443, Sept. 7, 1909.

It has long been recognized as desirable to hold the sinkers forward against the fabric in such a manner that the said sinkers may yield or give slightly under stress of the fabric though normally held yieldingly against the same. The object has heretofore been accomplished by the use of a spring band surrounding the sinkers but the use of a spring band is not entirely satisfactory especially when reverse plating. The sinkers, uniformly urged forward toward the needle circle by the spring band, do not permit the use of flopper cams to give to certain of the sinkers an earlier or differentiated movement with relation to others of the sinkers, necessary when reverse plating with sinkers.

In the drawings:

Fig. 1 is an inverted plan view of the sinker cap used in connection with one form of the invention;

Fig. 2 is a view in side elevation of the said sinker cap;

Fig. 3 is a view, partly in section, taken on line 3—3, Fig. 1;

Fig. 4 is a view, in section, taken on line 4—4, Fig. 1;

Fig. 5 is a view similar to Fig. 2 of another form of the invention;

Fig. 6 is a view similar to Fig. 1, of said other form; and

Fig. 7 is a sectional view taken on line 7—7, Fig. 6, showing the relative positions assumed by the sinkers and needles while they are traversing the non-knitting or idle portion of the raceway.

The numeral 1 represents the sinker cap as a whole, 2 and 3 fixed cams for normally controlling the sinker movements at the knitting point both for circular and reciprocating knitting, which said cams 2, 3 are secured to an overhanging flange 1' of the sinker cap. Sectional cams 4 overlapping at 4' constitute a continuation of the cam 3 and are mounted for movements to and from the forming fabric as about to be described. A raceway 5 is defined by walls 5' the outer of which constitutes a cam integral with or secured to the flange 1' while the other or inner wall forms the outer surfaces of the cams 4. Sinkers 6 are provided with butts 7 which are received in and guided by the said raceway 5. The cams 4 as well as the cam 3 are reduced in thickness where they overlap at 3' and 4', and are received in the space or groove 9 between the butts 7 and the vertical edges 10 of the sinkers 6. The said cams 4 have surfaces 8 at their inner edges or margins which cam surfaces 8 are normally in

constant engagement with the vertical edges 10 of the sinkers, and by means presently to be described, maintain the said sinkers in yielding engagement with their wales.

The sinkers when passing the fixed cams 2, 3 move in a normal path and knit in the usual manner in conjunction with the needles (not shown). After passing the knitting point, i. e., after the old stitches have been knocked over by the sinkers cammed forward to their innermost limit by the tip 12 of either cam 2 in reciprocating knitting, and by the uppermost as shown in Fig. 1 in circular knitting, the said sinkers are permitted, as usual, to retract slightly as at 13 thereby to relieve the stitches held on the open needle latches from undue strain that might otherwise cause a rupture of the stitches or some of them. Thereafter in the knitting cycle the needles and sinkers maintain the same relative positions, i. e., with the old stitch on the latch of each needle and held below the sinker nibs 11.

If the cams 4 are not controlled as about to be described, streaks occasionally show in the fabric due to the fact that certain of the sinkers are frictioned more than adjacent sinkers, and remain forward against the fabric thereby tensioning their wales and robbing or pulling thread from adjacent wales which are not so tensioned by their sinkers.

The form of the invention disclosed in Figs. 1—4 has the particular object in view of avoiding the formation of such streaks in the knit fabric and to that end provides for yieldingly holding or maintaining the sinkers in forward position against the forming fabric, whereby the position of the sinkers as they pass around the needle circle through the non-knitting portion of the same, will not be dependent upon the relative frictioning of the sinkers but the said sinkers will be uniformly maintained or guided in their idle path of traverse between courses.

The means for yieldingly maintaining the sinkers in forward web-engaging position is disclosed specifically in Fig. 3 of the drawings wherein rods 14 are received in and guided by holes 15 provided in arms 16 upstanding from brackets 17 attached to the sinker cap 1 in any convenient manner as by screws. There are four such brackets shown in Fig. 1 one at each end of both sectional cams 4, 4. Each rod 14, as aforesaid guided by its bracket, has a block or shoe 18 threaded onto the inner end thereof, which block is adapted to engage a pin 19 upstanding from one of the cams 4 adjacent one end thereof. The normal engagement of the block or shoe 18 with a pin 19 is maintained by means of a coiled spring 20 which surrounds the rod 14 and at one end is in engagement with the outer arm 16 while at the other end presses

against a collar 21 adjustably held on the rod by means of a set screw 22. The coiled spring 20 by exerting pressure against the collar 21 maintains the block or shoe 18 constantly and 5 yieldingly against a pin 19 which normally seats within a recess 23 provided in the flange 1' of the sinker cap 1. Each pin 19 is under spring pressure in the same manner and the cams 4, 4 are consequently constantly urging the sinkers 10 forward against the forming fabric, thereby resulting in a constant and uniform pressure or tension being exerted by the sinkers on their wales especially so when the sinkers are passing through the idle or non-knitting portion 15 of the raceway, i. e., after the old stitches have been knocked over for one course and until the said sinkers again reach the mouth-piece for the next course of knitting. The even tensioning of the wales results in the knitting of uniform fabric 20 without streaks.

In Fig. 4 a sinker is shown which is supported by the stitch ring 24 of the cylinder 25 at its forward end, and by the sinker head 26 beyond or outside of the needle cylinder 25.

25 In the second disclosed form of the invention, Figs. 5-7, the numeral 50 indicates the sinker cap in general which cap has a flange 51 acting as a support for the sinker actuating cams. Around the inner circular edge of the 30 flange 51 is clamped a spring band or cam 52 which is held in place by the overlapping, fixed cam 53 as shown in Fig. 6. Opposite the mouth-piece (not shown) are positioned two thin fixed cams 54, 55 normally adapted to actuate the 35 sinkers at the knitting point. Superposed, or rather, in the assembled positions, underneath the said fixed cams 54, 55 are two cams 56, 57 which are yieldingly urged toward the axis of the sinker cap by leaf springs 58, 59 respectively. The spring 58 is attached to the sinker cap 50 by means of a screw or other means and at a point substantially midway between the ends 40 of the aforesaid cam 56. The spring 58 consists of two wings or arms extending to each 45 side of the point of attachment, the outer or free ends of which spring arms engage over pins 60, 61 respectively depending from radial extensions 62, 63 projecting outwardly from the cam 56. The extensions 62, 63 pass through slots or 50 cutouts in the sinker cap 50. The cam 57 has similarly projecting portions or radial extensions 64, 65, the latter only of which has a depending pin 66 engaged by the leaf spring 59 thereby 55 to urge the said cam 57 in a, more or less, radial direction toward the sinker cap axis. The cams 56, 57 where they overlap the fixed, thin cams 54, 55 are cut away as indicated by the dotted 60 lines 67, 68 adjacent the ends of the said fixed cams 54, 55 shown partly in dotted lines, whereby the cams throughout are of substantially uniform thickness.

65 Springs 68, 69 attached to the cap 50 at one end, engage by their free ends pins 70, 71 depending from radial projections 72, 73 of cams 74, 75 which projections 72, 73 extend through slots in the sinker cap as do the other cam projections. At 76 are shown the overlapping ends 70 of each said cam dovetailing into the adjacent end of the other.

75 Between the spring band or ring 52 and the sectional cams 57, 74, 75 and 56 is provided a raceway 77 for the sinkers or web-holders as they pass around with the needles from course

to course. The sinkers 78 have butts 79 which latter are received in the raceway 77.

In order to reverse plate the sinkers are given earlier forward movements in a manner similar to that disclosed in the patent to Stewart 1,602,786, Oct. 12, 1926, and the yarns are reversed in a manner similar to that disclosed in Fig. 6 of the said patent. The sinkers, or rather selected ones of them, have the earlier movements imparted to them through the agency of 10 flopper cams 80 pivoted at 81 and held away from the sinkers by springs 81 attached to a bracket 82 connected to the sinker cap 50, but urged forward to a position to engage the sinkers as desired which flopper cams at such times 15 impart an earlier forward movement to their sinkers by engaging additional butts 83 thereon, which butts are positioned at different levels to be engaged by their flopper cams 80. The 20 said flopper cams, six in number, have pins 84, 25 three of which project in an upward direction from, while the other three depend from their respective flopper cams. The pins 84 are engaged by suitable levers or other selectively controlled means (not shown). The sinkers, flopper 30 cams, and parts for controlling the movements of the same, are not, in themselves, a part of the present invention, but do combine in a novel manner with the yieldingly mounted, sectional cams normally urging the sinkers to a forward position through the agency of the several springs 58, 59, 68, 69.

35 Referring to Fig. 7 a view, partly in section, is shown to more clearly disclose the necessity for having the sinkers held in a forward position against the forming fabric. In the said Figure 7 a needle 85 and companion sinker 78 are in the relative positions they assume and hold when travelling in the circular portion of the raceway 77 between stitch forming movements at the 40 mouth-piece where the sinker cams 53, 54, 56 and flopper cams 80 determine the character of stitch to be knit by each sinker in cooperation with its needle. At such times, i. e., between courses, the needles and sinkers are in the relative positions shown in Fig. 7, and the last drawn stitches or loops are hanging upon the open latches 86 and within the throats 87 of the sinkers which latter are, as shown in Fig. 7, in a forward position with their throats substantially in alignment 45 with the backs of adjacent needles or slightly radially inward thereof in which position they maintain the stitches or loops under tension. If the sinkers are held in the position, Fig. 7, unyieldingly the stitches or loops will necessarily be 50 maintained under stress tending to rupture the yarn oppositely tensioned by the adjacent needles and sinkers and this is more especially true when tight stitches are being knit as the short 55 stitches break under the strain exerted by the sinkers and companion needles. As will be evident from inspection of Fig. 7 and also the Stewart patent, the reverse plating sinkers are provided with short noses, i. e., with little overhang as compared with the ordinary sinker 8 of the 60 Stewart patent. The short noses 88 herein disclosed permit yarn held thereby to slip off if the stitch is loosely held with the result that the needle latch adjacent thereto does not subsequently clear in the normal manner but the needle 65 tucks or accumulates loops.

70 The devices of the present invention overcome the mentioned difficulties by holding the short noses or nibs of the reverse plating sinkers forward against the fabric thereby preventing the 75

loops or stitches from slipping off the said nibs, and furthermore, when knitting a tight stitch, the sinkers are permitted to yield or recede from the needles sufficiently to prevent rupture of the held stitches or loops.

The operation may be briefly summarized as follows:

In the first form, disclosed in Figs. 1-4, the sinkers traverse the raceway in the direction of the arrow, Fig. 1, first moving outwardly in a radial direction away from the axis, thereafter again moving toward the said axis to the stitch knock-over point, then receding slightly to relieve the stitches, and finally remaining in the latter position with respect to the axis until the aforesaid cycle of movements for the following course of knitting is repeated. Throughout the circular part of the raceway the sectional cams yieldingly urge the sinkers forward against the stitches thus maintaining the forming wales under even tension. The sectional cams do not control the sinkers at the knitting point or from the time they are retracted and again advanced to knock-over the stitches, but resume control only after the sinkers 25 retract to relieve the stitches which retraction immediately follows the knocking over of the old stitches by the sinkers.

In the second form disclosed in Figs. 5-7, the sinkers traverse the circular path in the raceway 30 as they do in the first form except that sinkers are not retracted after the knock-over of the stitches or old loops, but remain in their forward web-engaging position though permitted to yield through the agency of the sectional cams. The sinkers 35 are relieved from the influence of the spring cams as they leave the circular part of the raceway, whereupon the cam 53 engages the sinkers, and in conjunction with a flopper cam 80 and/or a cam 54 or a cam 55 retracts and again advances the 40 said sinkers thereby assisting in the formation of stitches for the following course of knitting.

Although the spring cams disclosed in Figs. 1-4, inclusive, are primarily intended to be used for plain knitting, and while the corresponding 45 spring cams disclosed in Figs. 5, 6, and 7 are primarily intended to be used for reverse plating or other knitting requiring special actuation or control of the sinkers or some of them; nevertheless the special cams, Figs. 1-4 inclusive, may be 50 used in conjunction with specially controlled sinkers and the spring cams of Figs. 5, 6, and 7 may be used for the knitting of plain fabric or plain plated fabric if desired.

While, in the foregoing description, the sinkers 55 have been referred to as moving in the raceway, such movement is relative, the sinkers themselves moving in a machine of the rotary needle cylinder type, and the cap moving or rotating in a machine of the stationary needle cylinder type.

60 The effect of maintaining the sinkers in a forward position by the means hereinbefore described, is to hold the nibs of the sinkers over the sinker wales of the newly drawn stitches, i. e., stitches drawn by the cooperation of needles and 65 sinkers immediately prior to the knocking over thereof by the knocking-over cam, thus preventing the formation of tuck or drop stitches. Furthermore, by yieldingly maintaining the sinkers in a forward position, as described, more uniform 70 fabric is knitted.

The sectional cams or their equivalent, are useful, where springs would not be suitable, e. g., wherever selective, differential movements of sinkers are desired for any purpose as for reverse 75 plating herein described with relation to the sec-

ond form disclosed, and also for sinker drop stitch work.

While specific terms have been employed to designate the essential elements of the present disclosure, it is to be understood that the scope of the said invention is not otherwise limited than by the claims appended, modifications of the parts and arrangements being within the intention and scope thereof.

We claim:

1. A sinker cap for use in a circular knitting machine, comprising sinkers and sectional cams therein for the control of the said sinkers throughout the knitting and non-knitting portions of the camway, and means acting through the sectional cams for yieldingly controlling the movements of the sinkers in a radial direction substantially throughout the non-knitting portions of the camway.

2. A sinker cap for use in circular machines of the independent needle type, cams therein for controlling the sinker movements so that stitches may be formed, and means for guiding the sinkers between successive stitch forming movements, said means including sectional cams urged forward or toward the needle circle, and maintaining the sinkers in a relatively forward position excepting where such sinkers are retracted and again advanced.

3. A sinker cap provided with a raceway for sinkers, bodily movable cams adapted to act upon sinkers between stitch forming movements thereof and yieldingly hold them in forward position to prevent the knitting of ruck or drop stitches.

4. A sinker cap provided with a raceway for sinkers, one wall of the raceway being divided into sections, each said section being yieldingly held in forward position, and thereby adapted to maintain sinkers yieldingly against the forming fabric.

5. In a sinker cap for use in circular knitting machines, cams adapted to guide the sinkers and impart stitch forming movements thereto, and other cams adapted to contact with the sinkers, in combination with means acting upon the said other cams yieldingly to maintain the said other cams in forward positions to hold the nibs of the sinkers over the sinker wales of newly drawn stitches.

6. A sinker cap having therein opposing cam surfaces providing a raceway therebetween, one of the cam surfaces being divided into a series of sections, each section being yieldingly urged forward or toward the needles.

7. A circular sinker cap having therein opposing cam surfaces providing a raceway therebetween, one of the cam surfaces being divided into sections, each section being yieldingly urged forward or toward the needles.

8. In a circular knitting machine sinker cap, a sinker raceway bounded on one side by a sectional cam, said cam being yieldingly mounted and adapted to press sinkers forward toward the needle circle to maintain their nibs over the sinker wales of newly drawn stitches.

9. In a circular sinker cap for use in circular knitting machines of the independent needle type, a sectional cam, the sections of which are yieldingly urged to move in a substantially radial direction toward the sinker axis thereby to maintain the nibs of the sinkers over the sinker wales of newly drawn stitches.
